Primary Examiner — George J Ulsh

Assistant Examiner — Katherine E Morris

(57) **CLAIM**

The ornamental design for a hand shaped towelette and container with lid assembly, as shown and described.

DESCRIPTION

FIG. 1 is a top front perspective exploded view of a hand-shaped towelette and container with lid assembly, showing my new design;

FIG. 2 is a bottom front perspective exploded view thereof;

FIG. 3 is a front elevation exploded view thereof;

FIG. 4 is a rear elevation exploded view thereof;

FIG. 5 is a right side elevation view thereof;

FIG. 6 is a left side elevation view thereof;

FIG. 7 is a top plan exploded view thereof;

FIG. 8 is a bottom plan exploded view thereof; and,

FIG. 9 is a top front perspective view thereof, shown in an assembled condition.

The claimed design includes a mirror image of the embodiment depicted.

1 Claim, 5 Drawing Sheets
